UNITED STATES PATENT OFFICE.

ISAAC BAAS, OF NEWARK, NEW JERSEY, ASSIGNOR TO AMERICAN TYPE FOUNDERS COMPANY, OF JERSEY CITY, NEW JERSEY, A CORPORATION OF NEW JERSEY.

TYPE-MOLD.

No. 902,196.

Specification of Letters Patent.

Patented Oct. 27, 1908.

Application filed May 25, 1908. Serial No. 434,901.

To all whom it may concern:

Be it known that I, ISAAC BAAS, of Newark, in the county of Essex and State of New Jersey, a citizen of the United States, have 5 invented a new and useful Improvement in Type-Molds, of which the following is a specification.

My invention relates to type founding machines, more especially to a type mold adapted to cast type for use in typesetting machines. In such machines slits are ordinarily provided each to receive its own type, the mouth of each slit being partially closed by projections arranged in a manner peculiar to 10 itself so that type having corresponding nicks registering with such projections and fed by automatic means will fall into the slit and may thus be found at the proper time by the type setting apparatus. Such machines of course must be supplied with type having various setwise dimensions and the difficulty heretofore has been to construct a mold which with a reasonable amount of 15 facility may be changed to supply type having different arrangements of nicks according to the particular letter which the type is to carry. For this purpose a mold has heretofore been constructed as shown in patent to H. Barth, No. 546,503, dated September 20 17, 1895, but in this case in practice a complete mold is provided for each character. As there are ninety characters ordinarily in a font it is evident that ninety molds are 25 provided which are expensive to construct and also require considerable time in their adjustment and re-adjustment. This adjustment of course must take place while the mold is cool enough to handle and hence there must be considerable delay after the 30 required number of type has been cast with one mold before another mold can be substituted for it. Moreover, in changing the mold accuracy of adjustment is very difficult to attain.

40 My invention relates to means whereby instead of providing a complete mold for each letter a key piece only is provided for each letter and for each setwise dimension of a letter.

45 My invention will be understood by reference to the drawings, in which—

Figure 1 is a perspective view of a mold embodying my invention, the cover and matrix being omitted. Fig. 2 is a detail of

the key piece showing also a means by which 55 it may be attached to the cheek piece. Fig. 3 is a view of the plunger or body piece. Fig. 4 is a fragmental section on line 4—4 of Fig. 1. Fig. 5 is a view in perspective of a type cast in the mold. Fig. 6 shows another key piece with its base, and Fig. 7 shows the type cast when using the key piece shown in Fig. 6.

A is the base plate of the mold.

B, B¹ are cheek pieces which occupy the 65 usual position as shown in patent to Barth above described. The front end of the cheek piece B, however, is recessed as at b and adapted to receive the base or attaching means of such a key piece as is shown in 70 Fig. 2. This key piece comprises a plate C carrying along its upper edge projections c. It will be seen by comparing the key piece in Fig. 2 and that in Fig. 6 that the projections c in the one case are longer 75 than the projections c in the other case and in different position, although the key pieces as a whole are of the same dimensions, that is, they are of the same width and of the same dimension measuring from the tip of 80 the projections down to the lower edges of the key pieces. In order to attach each key piece to the cheek piece where the cheek piece has such a recess as b, each key piece is provided with a base c¹ of proper dimensions to set into the cavity b in the face of 85 the cheek piece B and it is there held in place by set screws b². The plate C and its projections c are together of sufficient height to reach to the top of the cheek piece but 90 no higher as the key piece as a whole must not interfere with the movement of the mold cover.

D is the plunger or body piece which is 95 of ordinary construction as shown in the Barth patent above referred to, except that it is not the full thickness of the type body, and it moves between a line drawn across the key piece at the root of the projection c to a line on a level with the top of the 100 cheek pieces so as to eject the type from the mold. It therefore with the surfaces between and on each side of the projection c forms one wall of the mold and exposes only so much of the key piece as comprises 105 the projections c with the aforesaid surfaces between. Thus the side of the mold opposite the cheek piece B¹ is made up of the

projections *c* forming part of the key piece and so much of the cheek piece *B* as is exposed between the projections.

When it is desired to cast a type having less or greater setwise dimension or a different combination of nicks it is only necessary to remove the key piece *C* which may be done by loosening the screws *b*², sliding the base of the key piece out from the recess *b* in the cheek piece *B*, sliding another key piece into position and clamping it by means of the screws *b*² and then adjusting the stroke of the plunger or body piece so that in its lowest position it will be upon a line along the root of the projections *c*.

As indicating the resulting change in the type, attention is called to Fig. 2 which shows a key piece, Fig. 5 which shows a type cast with the assistance of such a key piece, Fig. 6 where a key piece is shown having projections differently located but differing in height, and Fig. 7 where the type cast therefrom is shown. It will be seen that the type differ in setwise dimension from each other and that the position of the nicks differ. The adjustment of the movement of the plunger or body piece may be made in any known way.

I have shown above a simple embodiment of my invention but in its broadest aspect it may be embodied in other ways which will occur to those skilled in the art, for so far as I am aware a mold has never been so constructed that any one of a number of key pieces may be used with it to form a portion of a mold, nor has a detachable key piece ever been constructed, that is, a key piece which may be located in a mold and held in place to form part of that mold for the purposes above described. Moreover, while I have described a key piece with a base portion adapted to set into a recess it is evident that such a holding means is not essential, nor is my invention solely adapted to a mold of the kind shown in the Barth patent although such a mold is eminently well fitted to receive a detachable key piece such as I have described.

What I claim as my invention is:

1. In a type mold, a cheek piece, a key piece having a series of projections extending from one edge thereof and with said cheek piece forming one side of the mold cavity, and means whereby said key piece

may be held in place against said cheek piece.

2. In a type mold, means for casting type provided with nicks comprising a cheek piece and a key piece having a series of projections extending from one edge thereof and, with said cheek piece forming one side of the mold cavity, said key piece being attached to said cheek piece and detachable therefrom.

3. In a type mold, a plate provided with projections mounted thereon, said projections being adapted to lie within the mold cavity and against one side thereof, and means whereby said plate is detachably secured to hold said projections in place in said mold.

4. A cheek piece provided with a recess and a key piece provided with a base adapted to set into the recess in said cheek piece, and means for holding it therein, said key piece being also provided with a series of projections extending from one edge thereof into the mold cavity whereby type cast in said mold may be provided with a series of nicks, as set forth.

5. In a type mold system, a series of key pieces of the same dimensions each having a given number of projections similarly arranged and located thereon, the projections on one key piece being longer than those on another, as described.

6. In a type mold system, a series of key pieces of the same dimensions, each having a number of projections arranged along one edge thereof, the projections on one key piece differing in arrangement from those on another key piece.

7. In a type mold system, a series of key pieces of the same dimensions, each having a number of projections arranged along one edge thereof, the projections on one key piece differing in length from those on another key piece.

8. In a type mold system, a series of key pieces of the same dimensions, each having a number of projections arranged along one edge thereof, the projections on one key piece differing both in arrangement and length from those on another key piece.

ISAAC BAAS.
